UNITED STATES PATENT OFFICE.

LEWIS S. HAYES, OF CORTLAND, NEW YORK.

KNOCKDOWN BOOK-CASE AND DESK.

SPECIFICATION forming part of Letters Patent No. 431,695, dated July 8, 1890.

Application filed September 21, 1889. Serial No. 324,599. (No model.)

To all whom it may concern:

Be it known that I, LEWIS S. HAYES, of Cortland, in the county of Cortland and State of New York, have invented certain new and

5 useful Improvements in Knockdown Book-Cases and Desks; and I do hereby declare the following to be a full, clear, and exact description of the invention, such as will enable others skilled in the art to which it applies to make and use the same.

10 My invention relates to an improvement in knockdown book-cases and desks.

The object is to provide a combined book-case and desk which may be packed in a compact form for shipment, thereby reducing the cost and liability to injury, and which will, when set up for use, present an attractive and finished appearance.

15 With these ends in view my invention consists in certain features of construction and combinations of parts, as will be hereinafter described, and pointed out in the claims.

In the accompanying drawings, Figure 1 represents the combined book-case and desk 20 set up for use. Fig. 2 represents the same in its compact form ready to be boxed, and Figs. 3 and 4 represent certain of the parts in detail.

A represents a casing of rectangular form 25 closed upon its ends and back and open at its front, the same being provided with shelves a, removably secured therein for the reception of books, the same forming the book-case portion of the combined book-case and desk. The bottom B of the casing A is located a short distance above the bottoms of the ends of the casing, so that the latter form legs to support the case, and also provide for the reception between them of the shelves a 30 and the ornamental piece at the top of the desk, which will be hereinafter referred to. By preference the bottom B is located at such a distance above the bottoms of the ends of the casing that the thicknesses of the shelves a 35 and ornamental piece referred to when laid flat against the under side of the bottom will just about fill the space between said ends.

An apron or foot-piece b is secured to the casing A to form a neat finish at the base.

40 The top C of the casing A is preferably left open, as shown at c, beneath the base of the desk portion for the purpose of saving lum-

ber and rendering the whole case lighter. The said top C projects laterally beyond the casing A at its ends and front to form a neat 55 finish.

A desk portion D, provided with a hinged front d, capable of being turned down into position to be used as a writing-desk, is fitted at its base to rest on the top C and slightly 60 over the edge of the opening c, and is in height equal to or nearly equal to the width of the casing A, measured between the inner walls of its ends. The width of the desk portion D is about the height of the space within the 65 casing A, so that when the desk portion D is turned upon its side and the shelves removed from the casing A the desk portion may be inserted within the casing A, as shown in Fig. 2, forming an easy fit therein. 70

The upper portion of the desk D is preferably constructed as a shelf or recess E for the reception of papers or bric-a-brac, and its top e is also placed a short distance below the top of its ends to form a shelf for the reception of bric-a-brac. 75

On either or both sides of the desk portion D (in the present instance shown on the left-hand side as the person faces the drawings) are provided shelf and ornamental sections 80 F and G, as follows: The portion F is constructed to rest on the top C of the casing A and to rest adjacent to the end or side of the desk portion D. It consists of a back f, a top forming a shelf f', the same being preferably 85 constructed in the form of a bracket, and a side or end ornamental arm f''. The part G is constructed to rest on the part F and adjacent to the end or side of the desk portion, and consists of a back g, two shelves g', and 90 a front ornamental piece g'', the latter having an opening g''' therethrough to show whatever ornament may be placed on the lower shelf g' or to gain access to the said shelf. When set up, the back of the desk portion D and 95 the backs of the parts F and G will occupy positions in the same plane and form to all appearances a solid back to the entire upper portion of the combined book-case and desk, and of such width as to correspond with the 100 width of the book-case proper. The upper portion is further ornamented by a rail H, which fits along the tops of the backs of the portions D and G and is removable there-

from, and the ends of the said rail portion are further ornamented by knobs I, removably secured thereto. The rail H, with its knobs removed therefrom, is adapted to be packed beneath the bottom of the casing A, in connection with the shelves a, as hereinbefore referred to. The parts F and G, the former being turned so that its arm f² shall occupy an upright position alongside of the part G, as shown in Fig. 2, are so constructed as to be received within the recess E of the desk portion D when the latter is packed within the casing A. Thus the entire book-case and desk when packed for shipment is the size of the book-case portion only, and when the latter, with its desk portion packed therein, as described, is boxed, the whole may be transported to any distance with little or no liability to injury, and may be handled much more readily than when occupying its full size. It will further be noted that by constructing the desk portion of a height corresponding to the width of the book-case portion the several parts are well proportioned, while the filling out of the desk portion by the lesser portions F and G gives the whole structure a unique and attractive appearance.

Having thus fully described my invention, what I claim as new, and desire to secure by Letters Patent, is—

1. A knockdown book-case and desk comprising a book-case section, a desk-section proper, and one or more supplementary desk-sections having backs to form a continuation of the desk-section proper, the book-case sec-

tion being provided with removable shelves and adapted to receive the desk portion proper therein, and the desk portion proper adapted to receive the supplementary section or sections within itself in the book-case, substantially as described. 40

2. A knockdown book-case and desk comprising the book-case A, the desk portion D, and the supplementary desk portions F and G, with backs f g, the several parts A, B, F, and G being detachable from each other, and the case A constructed to receive within it the parts D, F, and G when detached and folded, substantially as described. 45

3. The knockdown book-case and desk, comprising the book-case A, with its removable shelves, the desk portion D, the supplementary desk portions F and G, arranged at the side of the desk portion D and detachable therefrom, and a rail portion H, the casing A being provided with a space underneath its bottom for the reception of the shelves and railing, the space within the casing A being adapted to receive the desk D when turned on its side, and a recess within the desk D 55 being adapted to receive the supplementary portions G and F when the latter are turned partially over, substantially as described.

In testimony whereof I have signed this specification in the presence of two subscribing witnesses. 60

LEWIS S. HAYES.
